No. 677,982.

Patented July 9, 1901.

J. T. HEFFERNAN.

PISTON VALVE.

(Application filed Jan. 18, 1901.)

(No Model.)

UNITED STATES PATENT OFFICE.

JOHN T. HEFFERNAN, OF SEATTLE, WASHINGTON.

PISTON-VALVE.

SPECIFICATION forming part of Letters Patent No. 677,982, dated July 9, 1901.

Application filed January 18, 1901. Serial No. 43,775. (No model.)

To all whom it may concern:

Be it known that I, JOHN T. HEFFERNAN, a citizen of the United States, residing at Seattle, in the county of King and State of Washington, have invented certain new and useful Improvements in Piston-Valves, of which the following is a specification.

My invention relates to piston-valves; and it has for its object to provide a new and improved construction whereby such valves will be steam-tight and whereby they will be free in operation and not liable to get out of order or to wear or stick; and to these ends my invention consists in a piston-valve embodying the features of construction arranged and operating substantially as hereinafter more particularly set forth.

Referring to the accompanying drawings, Figure 1 is a vertical longitudinal section through the steam-chest and valve, showing the construction and arrangement of the parts. Fig. 2 is a part end and part sectional view showing the bridges and ring attached to the end of the valve; and Fig. 3 is an end view of the lining or bushing, showing rings in dotted lines.

In the use of piston-valves it is very important that they should be steam-tight and at the same time that they should be so constructed and arranged that they will not bind or produce too much friction, and it is the object of my present invention to provide a piston-valve which shall be simple, cheap, and effective in construction and which shall avoid the objections named, and I have illustrated a preferred embodiment of my invention in the accompanying drawings.

Referring to the drawings, 1 represents a valve-chest having ports or passages 2 leading to a steam-cylinder 3, and these ports are controlled by the valves 4, connected together in the present instance by a rod 6. Each of these valves consists of a body portion 5, forming the valve proper, and extending on opposite sides therefrom are a series of arms or bridges 7, and these are preferably joined at their outer ends by a ring 8, and in actual construction all these parts are preferably cast or formed in one piece.

Arranged in connection with each valve are the valve-linings 9, which may be of any

suitable or usual material and are preferably provided with a flange 10 and with steam ports or openings 11, 11^a, communicating with the ports or passages 2. Arranged on either side of these ports or passages 11, 11^a are recesses or grooves 12 in the inner face of the lining, and in these recesses or grooves are sprung the packing-rings 13, in the present instance two being shown on each side of the port 11; but the number of rings of course can vary according to the requirements of any particular case. These rings are slightly smaller than the face or circumference of the valve-body 5, and in order to aid in holding them up against the surface of the valve I construct the lining or bushing so that the rings will not be subjected to pressure from the high-pressure steam, which would tend to set the rings in the grooves. In order to accomplish this, I have shown the linings or bushings 9 as provided with a passage 14, opening into the exhaust-chamber 15 of the steam-chest, and connected with this passage 14 is an opening 16, leading to each groove or recess 12 in the lining, and when two packing-rings are used, as shown, I preferably arrange this opening near the adjacent sides of the two rings, as shown.

This being the general construction of the valve, its operation will be readily understood, and it will be seen that the rings 13, arranged on either side of the port 11 in grooves in the bushing, bear upon the valve-body 5 and make a steam-tight joint, and they are subjected to pressure from the exhaust-steam through the passage 14 and the opening 16 into the grooves in the face of the bushing. The arms or bridges 7, extending on either side of the body of the valve, serve to retain the packing-rings in position as the valve reciprocates in one direction or the other, and the ring 8 maintains the arms or bridges in proper relation and prevents their bending or yielding, while they interfere in no practical way with the passage of the steam or other fluid through the valve.

It will be understood, of course, that the form of the rings can be varied and any number of them can be used according to the requirements of any particular case and still embody the essential features of my inven-

tion, which consist, broadly stated, in providing a bushing or lining with internal grooves to receive the packing-rings and connecting the grooves by suitable openings and 5 passages with the exhaust-chamber, so that the steam will not set the rings in the grooves, but will aid in holding them in position to make a steam-tight packing. It will be observed that the rings are carried in grooves 10 in a lining, which lining can be used in any cylinder.

What I claim is—

1. The combination with a steam chest and valve, of a bushing provided with grooves 15 having rings arranged in the grooves, and passages connecting the grooves with the exhaust-chamber of the steam-chest, substantially as described.

2. The combination with a steam chest and 20 valve, of a bushing provided with a steam-port and grooves arranged on either side of the steam-port, packing-rings arranged in the grooves, a passage in the bushing communicating with the exhaust-port, and openings

from the passage to the grooves, substantially 25 as described.

3. The combination with a steam-chest, of a bushing having grooves in its inner face, packing-rings arranged in the grooves, a valve 30 provided with bridges extending therefrom, and a ring supporting the outer ends of the bridges, substantially as described.

4. The combination with a steam-chest, of a bushing having a steam-port and recesses on either side, packing-rings arranged in the 35 recesses, a passage communicating with the said recesses and with the exhaust-port, and a valve having bridges extending on either side thereof, the bridges being connected to a ring at their outer ends, substantially as 40 described.

In testimony whereof I have signed my name to this specification in the presence of two subscribing witnesses.

JOHN T. HEFFERNAN.

Witnesses:

L. J. VETLENTHAL,
JOHN JAMES.
